CLAIM

A new original design for pull-up pants, as shown and described herein.

DESCRIPTION

FIG. 1 is a perspective view of the pull-up pants showing my new design;

FIG. 2 is a front elevational view, the rear elevational view being a mirror image thereof;

FIG. 3 is a side elevational view, the opposite side elevational view being a mirror image thereof;

FIG. 4 is a top plan view thereof;

FIG. 5 is a bottom plan view thereof; and,

FIG. 6 is a perspective view, with the sides cut away to expose the interior region.
